US00D546313S

(12) **United States Design Patent** (10) **Patent No.:** **US D546,313 S**
Lheem (45) **Date of Patent:** **** Jul. 10, 2007**

(54) **MOBILE PHONE**

(75) Inventor: **Ji Youn Lheem**, Gyeonggi-do (KR)

(73) Assignee: **LG Electronics, Inc.**, Seoul (KR)

(**) Term: **14 Years**

(21) Appl. No.: **29/255,419**

(22) Filed: **Mar. 9, 2006**

(51) **LOC (8) Cl.** **14-03**

(52) **U.S. Cl.** **D14/138; D14/496**

(58) **Field of Classification Search** **D14/137, D14/138, 147-148, 247-248, 144, 496, 156, D14/341-347, 191, 192; 379/433.01-433.13; 455/575.4, 566, 575.1, 556.1, 556.2, 90.3, 455/41.2; D21/329, 331, 333; D16/208**

See application file for complete search history.
